UNITED STATES PATENT OFFICE.

GEORGE H. TAYLOR, OF NEW YORK, N. Y., ASSIGNOR TO THE KURSHEEDT MANUFACTURING COMPANY, OF SAME PLACE.

DESIGN FOR PLAITED FABRIC.

SPECIFICATION forming part of Design No. 30,974, dated June 6, 1899.

Application filed April 26, 1899. Serial No. 714,618. Term of patent 7 years.

To all whom it may concern:

Be it known that I, GEORGE H. TAYLOR, a resident of the city, county, and State of New York, have invented and produced a new and original Design for a Plaited Fabric, of which the following is a specification, reference being had to the accompanying drawings.

The substantial feature of my design is a plaited fabric wherein the plaits in their upper part have a laterally-waved or zigzag appearance, while the lower part of the plaits runs in a straight line, like ordinary accordion plaits, the upper edges of the straight as well as of the laterally-waved part of the plaits being on the same plane throughout.

In the drawings, Figure 1 represents a top view of my design, *a* designating the straight part of the plaits and *b* indicating the zigzag portion of them. Fig. 2 is a side view of the fabric embodying my design. 20

Having described my invention, what I claim is—

The design for a plaited fabric, substantially as herein shown and described.

GEORGE H. TAYLOR.
